CLAIM

The ornamental design for a buckle, as shown and described.

DESCRIPTION

FIG. 1 is a front perspective view of a buckle showing our new design;

FIG. 2 is a front view of the buckle;

FIG. 3 is a rear view of the buckle;

FIG. 4 is a right side view of the buckle;

FIG. 5 is a left side view of the buckle;

FIG. 6 is a top view of the buckle; and,

FIG. 7 is a bottom view of the buckle.

The broken lines in the drawings represent portions of the buckle that form no part of the claimed design.

1 Claim, 7 Drawing Sheets
